FLUID REGULATOR

James Howard Frickie, San Francisco, Calif.

Application October 21, 1933, Serial No. 694,559

4 Claims. (Cl. 60—64)

This invention relates generally to devices for automatically regulating the flow of elastic fluids, such as steam, particularly where reduced pressure is to be supplied from a relatively high pressure source.

It is a general object of the invention to provide a regulating device of the above character, which will be characterized by freedom from operating difficulties and repairs for long periods of service.

A further object of the invention is to provide a pressure regulator which will be of rugged and simple construction, and which will avoid the use of conventional pressure diaphragms.

Another object of the invention is to provide apparatus which will serve to maintain a constant flow of steam thru a prime mover or like device, and at the same time function as a pressure reducing means.

Further objects of the invention will appear from the following description in which the preferred embodiment of the invention has been set forth in detail in conjunction with the accompanying drawing.

Referring to the drawing:

Figure 1 is a side elevational view illustrating diagrammatically one manner in which my device may be connected in conjunction with a prime mover, to control flow of steam there-through at a reduced pressure.

Fig. 2 is a side elevational view, in cross section, illustrating a regulating device incorporating the present invention.

Fig. 3 is a cross sectional detail taken along the line 3—3 of Fig. 2.

Referring first to Figs. 2 and 3 of the drawing, the device illustrated therein consists of a body 10, having an inflow opening 11 for connection with a source of high pressure steam or like elastic fluid and an outflow opening 12, for connection with the low pressure system. Mounted within the body 10 are the valve seats 13 and 14, which are generally cylindrical in form, and which are alined on a common axis. In the modification illustrated the valve seats 13 and 14 are constructed as parts separate from the body, and are detachably mounted with respect to the inner body portion 16, by suitable means such as threaded connections 17 and 18. Valve seat 13 is shown provided with an upper flange 19 which is shaped hexagonally, or otherwise formed to facilitate application of a wrench or like tool. The lower seat 14 is likewise shown provided with similarly formed flange 21.

Fluid flow thru the valve seats 13 and 14 is

preferably by way of openings or ports 22 and 23. It will be noted that two annular rows of ports are provided, and these rows are staggered with respect to each other. The lower side of the body 10 is preferably closed by a removable plate 24, which affords access to the interior of the body for the removal of valve seat 14. The upper side of the body is likewise enclosed by a removable head 26, which affords access for the removal of valve seat 13.

Extending concentrically with respect to the valve seats 13 and 14, that is, in alinement with the common axis of these seats, there is a tubular plunger 27. Mounted or formed upon this plunger, are the two spaced pistons 28 and 29, which slidably fit within the valve seats. These pistons are shown provided with conventional split piston rings 31, to promote sealing engagement. The spacing between pistons 28 and 29 is such that when plunger 27 is moved downwardly, ports 22 and 23 are uncovered by an equal amount, to permit flow of steam or like fluid from the inflow opening 11, to the outflow opening 12. Downward movement to full open position can be arrested by suitable means such as a lug 32, formed upon the inner side of plate 24. Upward movement from full open position serves to reduce the exposed area of ports 22 and 23, until a position is reached where the ports are entirely sealed by the pistons.

The upper extended end portion 34 of plunger 27 is slidably fitted within a cylinder bore 35, formed in the head 26. Suitable means such as split piston rings 36 are provided so that the upper end of the plunger 27 in effect forms a piston having a relatively sealed fit within the cylinder bore 35. Varying pressures to modify operation of the device can be applied to the cylinder bore 35 by means of a pipe connection 38.

In order to serve as resilient means for normally urging plunger 27 together with the pistons 28 and 29 towards open position, a compression spring 39 is disposed within the plunger. To adjust or vary the tension applied to spring 39, a screw 41 is threaded into the head 26. Leakage about this screw is prevented by conventional means such as a packing gland 42, and the outer end of the screw can be provided with suitable means such as a hand wheel 40, for its adjustment. The inner end of the screw is provided with a thrust shoulder 43, upon which the upper end of spring 39 is seated. The lower end of this spring seats upon the lower end portion of the plunger 27.

It will be noted from Fig. 2 that the inner faces 55

of pistons 28 and 29 are of substantially the same area. In other words with respect to any given pressure applied to the device from the inflow side, the fluid pressures upon the pistons 28 and 29 are equal and in opposite directions. However with respect to the outflow pressure, piston 29 presents a considerably larger area than piston 28, particularly since the upper end of the plunger is sealed with respect to the cylinder bore 35. 10 Therefore for any particular outflow pressure the fluid forces in opposite directions upon the two pistons will be unequal, and a differential force component will be created tending to move the pistons toward closed position.

15 Operation of my device as a simple pressure regulator can now be described:—It will be presumed that the inflow opening 11 is connected to a source of high pressure steam, while the outflow opening 12 is connected to a system to which 20 low pressure steam is to be supplied. When the pressure upon the outflow side is between desired limits, for a given steam consumption from the low pressure system, pistons 28 and 29 assume an intermediate position in which the pressure of 25 spring 39 balances the differential force component created by virtue of the different areas exposed by the pistons to the outflow pressure. In the event steam consumption on the outflow side of the device increases, thus causing a fall in the 30 outflow pressure, the differential force component upon the two pistons decreases, thus causing the spring 39 to move the pistons downwardly to expose a greater area of ports 22 and 23. Thus an increased flow of steam is admitted to the inflow side, to maintain the outflow pressure. Conversely if the outflow pressure tends to increase, as for example due to a decrease in the consumption of steam in the outflow system, the 35 differential force component upon the pistons increases to move the pistons upwardly, thus decreasing the exposed area of the ports 22 and 23. In the event steam consumption in the outflow system ceases entirely, the pistons will move upwardly sufficiently far to entirely seal the device against further flow. Thus the outflow pressure is maintained between desired limits irrespective of variations in the rate of consumption 40 of steam from the outflow system, and also irrespective of pressure changes on the high pressure side.

As shown in Fig. 1, it is also possible to utilize my device as a combined governor and pressure reducing valve. In this case the regulator is indicated generally at 1, and serves to regulate supply of steam to an engine, turbine or like prime mover 2. The exhaust from the prime mover 2 is shown connected to a condenser 3. Pipe 38 from the regulator is shown connected between the prime mover 2 and the condenser 3. With such an arrangement it is apparent that the pressure within the cylinder bore 35 of the regulator will vary in accordance with back pressure upon the prime mover 2. Upon an increase in the pressure in cylinder bore 35, a force is 55 added to spring 39, tending to move pistons 28 and 29 towards open position. Thus when the exhaust pressure on prime mover 2 tends to increase, increased steam pressure in cylinder bore 36 tends to increase the amount of steam supplied to the prime mover, and conversely when the exhaust pressure tends to decrease, a lesser amount of steam is supplied. Thus my device in this instance will function as a governor, to maintain the amount of steam flowing thru the prime mover substantially constant, in addition

to the function of reducing the pressure from the steam supply.

I claim:

1. In apparatus of the character described, a prime mover, a pressure regulator connected between a source of high pressure steam and the prime mover, said regulator serving of itself to maintain the pressure of steam applied to the prime mover substantially constant, and a back pressure connection from the exhaust side of the prime mover to the regulator, to serve to modify the action of the regulator.

2. In a steam flow regulating device of the character described, a body having an inflow opening for connection with a source of relatively high pressure steam and also having an outflow opening for connection with a low pressure steam system, a pair of spaced cylindrical valve members disposed within said body and serving to establish communication between the inflow and outflow openings, said valve seats being in alignment and having ports extending laterally through the same, a tubular plunger extending axially through said valve seats, a pair of spaced cylindrical valve members carried by said plunger and slidably fitted within the valve seats, said valve members serving to regulate flow of steam through said ports dependent upon the positioning of the same, said valve members being substantially balanced with respect to inflow pressure and unbalanced to a substantial degree with respect to outflow pressure, sealing rings carried by said valve members and serving to seal the same relative to the seats, a cylinder formed within one side of the body and aligned with respect to the plunger, a piston formed on one end of the plunger and slidably fitted within said cylinder, a sealing ring carried by said piston and serving as the sole means to seal the piston relative to the cylinder, a compression spring disposed within said tubular plunger, one end of the bore of the tubular plunger being in communication with said cylinder and the other end of the bore being closed, and means for connecting said cylinder to an external source of pressure.

3. In apparatus of the character described, a prime mover, a pressure regulator connected between a source of high pressure steam and the prime mover, said pressure regulator serving of itself to maintain the pressure of steam supplied to the prime mover substantially constant, and including a chamber adapted to receive steam under pressure to modify the pressure delivered by the regulator to the outflow side thereof, and a back pressure connection from the exhaust side of the prime mover to said chamber.

4. In apparatus of the character described, a prime mover, a pressure regulator connected between a source of high pressure steam and the prime mover; said regulator including a flow control valve, means responsive to inflow and outflow pressures for actuating the control valve to maintain the outflow pressure substantially constant, a chamber adapted to receive steam from an external source, and a member urged by steam pressure in said chamber to apply force to the valve member in a direction to cause opening movement of the same; and a back pressure connection from the exhaust side of the prime mover to said chamber, whereby an increase in steam pressure on the exhaust side of the prime mover causes an increase in the supply of steam from the regulator to the prime mover.
